UNITED STATES PATENT OFFICE.

LOUIS MARCHAND, JR., OF PITTSBURG, PENNSYLVANIA.

FASTENING FOR THE ENDS OF WIRE CABLES.

985,915.

Specification of Letters Patent.

Patented Mar. 7, 1911.

Application filed October 2, 1909, Serial No. 520,670. Renewed November 22, 1910. Serial No. 593,723.

To all whom it may concern:

Be it known that I, LOUIS MARCHAND, Jr., a citizen of the United States, residing at Pittsburg, county of Allegheny, and State 5 of Pennsylvania, have invented certain new and useful Improvements in Fastenings for the Ends of Wire Cables; and I do hereby declare the following to be a full, clear, and exact description of the same, reference 10 being had to the accompanying drawings, forming a part of this specification, and to the figures and letters of reference marked thereon.

The present invention relates to devices 15 for securing the ends of wire cables within terminal sockets such as are ordinarily used in connecting cables with anchors or with parts to be supported by the cable.

The objects of the invention are to provide 20 a simple, cheap structure which will securely grip and hold the extreme end of a wire cable without introducing strains such as would tend to weaken the strands at any point.

25 A further object of the invention is to provide a means for anchoring cable ends in their sockets which may be readily utilized by linemen and others having charge of such work without the necessity of employing special tools or means for preparing either the cable end or the parts co-operating therewith, thus adapting the structure for use in guy-rope or cable work for trolley road installations, although it will be understood that it is not intended to limit the invention to this particular use.

Referring to the accompanying drawings—Figure 1 is a perspective view of one end of a 7-wire cable anchored in a terminal 40 socket in accordance with the present invention. Fig. 2 is a sectional view in a plane parallel with the major axis of the socket, the cable being in elevation. Fig. 3 is a perspective view of the internal anchor or 45 tapering plug on an enlarged scale. Fig. 4 is a similar view of the plug with its exterior surface recessed to receive the wires of the cable. Fig. 5 is a perspective view of the plug or anchor with the exterior surface

corrugated or roughened. Fig. 6 is a section 50 through the plug showing the internal surface threaded or roughened.

Like letters of reference in the several figures indicate the same parts.

The invention of the present application 55 is primarily intended for use in connection with guy wires or cables made up of a number of strands which surround a central wire or core such, for instance, as the 7-wire cable now in common use. It is the intention to so construct the parts that each wire 60 will be held and caused to bear its proportion of the total strain to which the cable is subjected and, at the same time, afford the means whereby the anchoring device is 65 prevented from squeezing out or releasing the ends of the wires either under excessive tension strains or upon the sudden release of strain.

The letter A indicates a terminal socket 70 or casting having its body portion of cylindrical or other appropriate shape externally but with a central longitudinal aperture of frusto-conical form tapering from the inner to the outer end of the casting. This frusto-conical aperture is well illustrated in Fig. 2 and indicated by the letter B, its smaller 75 end being preferably made of such diameter that it will receive cables of the largest size with which the device is adapted for use. Suitable eyes or loops such as C, C may be 80 conveniently formed integral with the socket or casting and extend rearwardly for the reception of anchoring bolts or other means whereby the socket or terminal casting is 85 held, but it will be understood that the terminal socket may be held in any ordinary or preferred manner.

The terminal end of the cable F which is to be secured in the socket is passed in 90 through the smaller end of the aperture and the wires forming said cable are spread and separated or given a conical formation by means of a spreader or plug G. This spreader or plug G is of frusto-conical form 95 with an external taper which corresponds to the taper of the aperture in the terminal casting or socket. The plug is provided

with a central bore g for the reception of the core of the cable and it is of such construction that when driven or drawn into the socket it will be sufficiently deformed to effectually grip the said core and become locked thereto.

In the preferred construction the plug or spreader is split longitudinally by a kerf H which extends entirely through one side of the wall and partly through the other side of the wall, whereby, as the plug is drawn or driven into the socket the two sides will be forced toward each other to grip the core at the same time that the exterior or sheath wires of the cable are gripped between the plug and wall of the aperture through the socket.

By locking the plug to the core of the cable and causing the parts to mutually coact in their gripping action, not only are the strands held with a uniform pressure and each caused to bear its proportion of the strain, but there is little or no danger of the anchor being released by a reverse movement of the cable with relation to the socket.

In the manufacture of the device for commercial purposes, it is designed that the taper of the socket and plug shall be so proportioned that the plug cannot be squeezed out of position by excessive strain and at the same time while the wires will not be cut or weakened the gripping action will be sufficient to hold them tight enough to withstand all strains they are capable of bearing. It is also designed that the terminal castings or sockets shall be of such size as to adapt them for use with cables of different sizes, it only being necessary to supply plugs or spreaders of proper size for co-operation with each particular size of cable or size of wire forming the strands of the cable.

In some instances it is found desirable to provide surfaces for contact with the wires which will bite or indent the wires between the gripping surfaces, for instance, where plugs or spreaders of extreme hardness are employed in connection with wires which are relatively soft and where this is desired the external surface of the plug may be roughened or ribbed, as illustrated at I in Fig. 5, or, said external surface may have positioning grooves for the ends of the wires, as shown at K in Fig. 4.

The grip of the plug or spreader upon the core of the cable may likewise be increased by roughening the interior surface of the plug or spreader conveniently by forming a screw thread L therein, as illustrated in Fig. 6.

While the additional gripping action due to the grooving of the surfaces of the plug is desirable in many instances it will be understood that this feature is not essen-

tial and may be dispensed with where the plug socket and wires of the cable are of approximately equal hardness.

The use of the invention dispenses with the necessity of employing soft metal fillers for the ends of the cable and, besides effecting a saving in wire the invention gives a maximum gripping and holding effect with the least possible liability of cutting the individual strands or of throwing a greater strain upon one strand than upon another.

Having thus described my invention, what I claim as new and desire to secure by Letters Patent of the United States, is:—

1. A connector of the character described, comprising a socket having a tapering aperture therethrough adapted to receive the strands of a cable, and a central collapsible spreader having its collapsible walls connected to simultaneously move longitudinally said spreader having a central longitudinal aperture therethrough adapted to receive and grip by collapsing thereon the core of a cable, and also having a tapering external strand engaging surface between which and the internal face of the socket the external strands of the cable are gripped the taper of the socket aperture and of the spreader being made to correspond whereby the pressure on the strands is distributed uniformly in the gripped area.

2. A connector of the character described, comprising an integral unyielding socket having a tapering aperture therethrough adapted to receive and grip the strands of a cable, and an integral spreader having an external tapering strand engaging surface between which and the tapering internal surface of the socket the external strands of a cable are gripped, said spreader having a central longitudinal aperture therethrough adapted to receive the core of a cable, the wall of said spreader being split longitudinally on one side whereby it is adapted to be collapsed by the external pressure of the strands and socket to grip the core and the taper of the socket aperture and of the spreader being made to correspond whereby the pressure on the strands is distributed uniformly in the gripped area.

3. A connector of the character described comprising an integral unyielding socket having a frusto-conical aperture therethrough adapted to receive the strands of a cable and a frusto-conical spreader having its tapered face formed with a plurality of spiral grooves, each extending from end to end of the spreader, said grooves being spaced apart and adapted to receive and position the external strands of the cable.

4. A connector of the character described comprising an integral unyielding socket having a frusto-conical aperture there-

through adapted to receive the strands of a cable and a frusto-conical spreader having an external cable strand engaging face and a central cable core receiving aperture adapted to receive and grip a single cable core strand, the wall of said spreader being split longitudinally and the wall of the aperture being roughened to grip the cable core the

taper of the socket aperture and of the spreader being made to correspond whereby 10 the pressure on the strands is distributed uniformly throughout the gripped area.
